UNITED STATES PATENT OFFICE.

WILLIAM H. WALDRON, OF NEW BRUNSWICK, NEW JERSEY.

PRINTING-MACHINE.

1,271,965.

Specification of Letters Patent.

Patented July 9, 1918.

Application filed May 22, 1917. Serial No. 170,185.

To all whom it may concern:

Be it known that I, WILLIAM H. WALDRON, a citizen of the United States, residing in New Brunswick, Middlesex county, State 5 of New Jersey, have invented Printing-Machines, of which the following is a specification.

This invention relates to apparatus for printing textile fabrics such as carpets and 10 more particularly rugs, in one or any desired number of colors so applied as to constitute a pattern.

One object of the invention is to provide a machine of the above noted type in which 15 the paint or colors may be applied to a plain rug or carpet by one or any desired number of print blocks reciprocating in a straight line and said invention particularly contemplates a novel form of block 20 for printing textile fabrics of the above noted class.

A further object of the invention is to provide novel means for applying the proper quantities of coloring material or 25 paint to the printing surface of a block and it is especially desired that said block shall be so constructed as to prevent its depositing coloring material upon the fabric at points where it is not desired.

30 Another object of the invention is to provide a printing block for use in a machine of the character above noted, which shall be particularly adapted for printing large bodies of woven and especially pile fabric, 35 together with novel means for preventing the accumulation of paint or coloring material at the edges of the blocks and for removing from the blocks the coloring material which has been offset thereon by reason 40 of contact with previously colored parts of the fabric.

These objects and other advantageous ends I secure as hereinafter set forth, reference being had to the accompanying drawings, in which, 45

Figures 1 and 2 are respectively end and side elevations, the latter partly in section, of a printing machine constructed according to my invention; and

50 Fig. 3 is a vertical section to some extent diagrammatic, further illustrating the detail construction of one of the printing blocks and its coöperating color supplying mechanism, forming part of my invention.

In the above drawings, 1 represents the 55 frame of a portion of my improved printing machine which includes guides 3 for the reception of reciprocating block carriers 2 consisting of two vertically movable members 5 operative in the guides 3, with a 60 transverse member 6 extending across the machine and having a printing block 4 secured to it. Mounted in suitable bearings carried by the frame is a transversely extending shaft to whose ends are fixed cams 65 11 for reciprocating the block carrier 2;— it being understood that, as shown in Fig. 2, there is one of these cams at each side of the machine, and as many complete block-printing units as may be required for the 70 work to be performed.

Each of the vertical members 5 has attached to its lower portion a roller 12 and these rollers are respectively operative on said cams so that as the latter are rotated 75 by the shaft, the block carrier 2 and with it the block 4 are vertically reciprocated.

The fabric to be printed is moved over a table 36 carried by the main frame and having at its edges suitable endless conveying belts 37 provided with upwardly projecting pins or prongs 38 which engage the edges of the fabric, although obviously other means may be provided for moving the latter through the machine. Suitable 85 mechanism, forming no part of the present invention, is provided to intermittently feed the conveying belts with the fabric through the machine, and it is to be understood that while I have illustrated but a single printing block and carrier with the associated mechanism, each machine as a matter of 90 fact is provided with a number of these, depending upon the number of colors to be applied and the pattern to be printed. 95

One important feature of my invention has to do particularly with the printing block 4, which consists of a back or body in the form of a relatively heavy iron plate or body 20 rigidly fixed to the transverse 100 members 6 of the carrier. The under face of this back has fixed to it in any suitable manner an engraved plate 21, usually of copper or equivalent material, in whose lower face is cut the particular design which 105 it is desired shall be printed by this particular printing unit. It is especially to be noted that the sides of this plate 21 are

projected beyond the sides of the block 4 and are curved upwardly as indicated at 22.

For applying the coloring material to the printing face of the block I provide a carriage 50 supported on wheels 51 operative on tracks 52 extending along the sides of the table. This carriage supports a trough 53 at whose ends are bearings for the support of a roller or brush 54 whereby liquid coloring material is transferred from the trough or fountain to the under face of the engraved plate 21 of the block.

Each of the carriage structures is provided with two doctors 55 and 56, respectively on opposite sides of the roller or brush 45 and each consisting, in the present instance, of a pair of bars 57 and 58, connected together in any suitable manner and having end trunnions or spindles 59 rotatably fitting suitable bearings at the ends of the carriage structure. The bars or plates 57 and 58 clamp between them a blade 60 and in the case of the doctor 55, a trough 61 projects outwardly from the bottom of the plate or bar 58 so as to catch the liquid collected by the blade 60 when this is moved in one direction over the engraved plate 21.

The second doctor 56 has a similar but oppositely projecting trough 62 connected to and extending outwardly from the bottom of its block or plate 57 in position to catch liquid removed from the engraved plate by its blade 60 when the carriage is moved in a direction opposite that in which liquid would be collected by the trough 61. By reason of the manner in which the troughs are mounted, they serve as weights which tend to rotate the doctors into positions in which their blades 60 are vertical and consequently the latter are at all times pressed into engagement with the surface of the engraved plate regardless of whether they are inclined on the one side or the other of a vertical plane passing through their trunnions.

Under conditions of operation a plain or unprinted body of fabric such as a rug or carpet is placed upon the pins of the endless 50 conveyers and is moved thereby under the first of the series of printing blocks. Suitable pigment is supplied to the color carriage 50 of this block or printing unit and said carriage is moved under said block in 55 the direction indicated by the arrow. Coloring material is then transferred by the roller or brush 54 from the trough 53 to the under face of the plate 21 and all of said material except that in the depressions of 60 said plate, is removed by the doctor 56, from which it runs back into the trough 53. The carriage is then moved in the reverse direction and when it is clear of the block, the latter is forcibly moved down by the cams 65 11 so that the coloring material in the de-

pressions of its plate 21 is applied to the fabric;—sufficient force being exerted upon the block to insure that said fabric is forced into the depressions and made to absorb or receive the coloring material therein.

After the block has been again raised to its upper position, the fabric is fed forward through a definite distance and thereafter subjected to the printing action of other similar blocks, which however, apply to it 75 other colors of paint or pigment at different portions of its surface, so that ultimately it has printed upon it a predetermined pattern.

Obviously the successive reciprocations 80 of the various blocks after the first, causes some of the coloring material previously applied to the fabric to be transferred to their surfaces and as the color carriage moves under each block, the plate 60 of the 85 doctor 55 scrapes or cleans this undesirable coloring material from said surface before fresh coloring material is applied thereto by the roll or brush 54. The mixed paints so removed are collected in the trough 61 90 from which they are withdrawn from time to time and at the same time the surplus paint removed by the blade of the doctor 56 is directed back into the trough or fountain.

If the plate 21 was plane or flat throughout its extent, the color applying roll or brush 54 in delivering paint to it would permit a mass of such material to accumulate along its sides or edges and this would be 100 transferred to the fabric when the block was moved down, thereby printing a line or otherwise marking said fabric in an undesirable manner. By turning up the edges or sides of the engraved plate 21 as indicated at 22, the doctor blade 60, by reason of the gravitational action of its trough 61 or some equivalent device, follows up said curved side and thus removes the coloring material, not only from the flat surface of 110 the block but also from a greater or less portion of the upwardly curved side extension, with the result that when the plate is brought into contact with the fabric, there is no mass of coloring material at its sides 115 as would otherwise be the case.

After having operated upon the engraved plate as the color carriage is moved under it, the doctors are swung into substantially vertical positions where they remain until, 120 as the carriage is moved to return to its normal position at the right of the block, they strike one curved side 22 of the plate 21 and are moved to the oppositely inclined positions shown in dotted lines. When the doctors have again acted upon the plate and thereafter assumed vertical positions, the reversal of the direction of movement of the carriage turns them into engagement with the second or right hand turned-up edge 22, 130

whereby as the carriage is moved under the block, they are swung into the positions shown in full lines in the drawings.

Regardless of the direction of movement 5 of the carriage, there is thus one doctor operating in advance of the color-applying roller or brush, to remove and collect any paint or coloring material off-set on the face of the plate from the fabric previously 10 printed by the other blocks, together with a second doctor which removes from the plate and returns to the fountain, all coloring material except that in the depressions of said plate.

15 I claim:—

1. The combination in a printing machine of a reciprocable printing block; means for applying coloring material thereto including a fountain reciprocable under 20 the block; a doctor for removing surplus coloring material from the block, said doctor being formed to cause the material removed to be delivered into the fountain when it moves over the block in one direction 25 and including means for separately collecting the removed material when it moves over the block in an opposite direction.

2. The combination in a printing machine 30 of a reciprocable block having a bottom printing face; a color applying device movable under said block and including a color applying roller; doctors mounted to act on the block on opposite sides of the roller respectively and each including means for separately collecting coloring material when moved over the block in one direction.

3. The combination in a printing machine 40 of a reciprocating block having a bottom printing face; a color applying device movable under said block and including a color applying roller; doctors mounted to act on the block on opposite sides of the roller respectively and including oppositely extending 45 containers placed to collect coloring material removed from the block.

4. The combination in a printing machine 50 of a reciprocable printing block; a color applying device reciprocable under said block; an oscillatory doctor mounted to act upon the printing face of the block in either of

two positions; with means for automatically reversing the position of the doctor after each of its engagements with the block.

5. The combination in a printing machine 55 of a reciprocable printing block; a color applying device reciprocable under said block; an oscillatory doctor mounted to act upon the printing face of the block in either of two positions; with means for automatically 60 reversing the position of the doctor after each of its engagements with the block, the same consisting of an upwardly projecting extension at the side of said block.

6. The combination in a printing machine 65 of a reciprocable printing block; a color applying device reciprocable under said block; an oscillatory doctor mounted to act upon the printing face of the block in either of two positions; means for automatically 70 reversing the position of the doctor after each of its engagements with the block; with a trough for separately collecting coloring material removed by the doctor when the latter occupies one of its two positions in engagement with the block.

7. The combination in a printing machine 75 of a reciprocable block; means for applying coloring material to said block; a reversible doctor for removing surplus material from the block, at least one curved side extension for the block extending away from the plane thereof; with means for causing the doctor to press against the printing face of the block and also to act on the surface 80 of the extension, said extension being formed to reverse the doctor when its direction of movement relatively to the block is reversed.

8. The combination in a printing machine 90 of a reciprocable block having two opposite upwardly curved edge extensions; means for applying coloring material to the under side of the block; a doctor for removing surplus coloring material from the block; and 95 means for causing said doctor to operate on the printing face of the block and also on said edge extensions, consisting of a trough placed to receive color removed by the doctor when this is operating in one direction. 100

In witness whereof I affix my signature.
WILLIAM H. WALDRON.
